US00D856045S

(12) **United States Design Patent** (10) **Patent No.:** **US D856,045 S**
(45) **Date of Patent:** **** Aug. 13, 2019**

(54) **DISPLAY STAND COMPONENT**

(71) Applicant: **Apple Inc.**, Cupertino, CA (US)

(72) Inventors: **Charles A. Schwalbach**, Menlo Park, CA (US); **Sheng Yang**, Mountain View, CA (US); **Russell John Kaaihue Heirakuji**, Cupertino, CA (US); **Carly Lynn Marasco**, Los Gatos, CA (US); **Michael Gorman**, Dublin, CA (US)

(73) Assignee: **Apple Inc.**, Cupertino, CA (US)

(**) Term: **15 Years**

(21) Appl. No.: **29/672,734**

(22) Filed: **Dec. 7, 2018**

Related U.S. Application Data

(63) Continuation of application No. 29/641,661, filed on Mar. 23, 2018, now Pat. No. Des. 835,440, which is a continuation of application No. 29/609,617, filed on Jul. 3, 2017, now Pat. No. Des. 813,576, which is a continuation of application No. 29/588,391, filed on Dec. 20, 2016, now Pat. No. Des. 792,133, and a continuation of application No. 29/588,390, filed on Dec. 20, 2016, now Pat. No. Des. 791,521, and a continuation of application No. 29/564,382, filed on May 12, 2016, now Pat. No. Des. 777,482, and a continuation of application No. 29/564,382, filed on May 12, 2016, now Pat. No. Des. 777,482, which is a continuation of application No. 29/537,088, filed on Aug. 21, 2015, now Pat. No. Des. 756,152, which is a continuation of application No. 29/507,269, filed on Oct. 24, 2014, now Pat. No. Des. 737,081.

(57) **CLAIM**

The ornamental design for a display stand component, as shown and described.

DESCRIPTION

FIG. 1 is a top front perspective view of a display stand component showing our new design;
FIG. 2 is a front view thereof;
FIG. 3 is a rear view thereof;
FIG. 4 is a left side view thereof;
FIG. 5 is a right side view thereof;
FIG. 6 is a top view thereof; and,
FIG. 7 is a bottom view thereof.

(Continued)

The dashed broken lines in the figures show portions of the display stand component that form no part of the claimed design.
